UNITED STATES PATENT OFFICE.

ANTON DVORAK, OF BERWYN, ILLINOIS, ASSIGNOR TO BEARDSLEE CHANDELIER MANUFACTURING COMPANY, A CORPORATION OF DELAWARE.

LIGHTING FIXTURE.

1,419,920.

Specification of Letters Patent. Patented June 20, 1922.

Application filed April 2, 1921. Serial No. 457,956.

To all whom it may concern:

Be it known that I, ANTON DVORAK, a citizen of the United States, and a resident of Berwyn, in the county of Cook and State 5 of Illinois, have invented certain new and useful Improvements in Lighting Fixtures, of which the following is a description, reference being had to the accompanying drawings, which form a part of my specification.

10 My invention relates more particularly to means for supporting and fastening separate pieces of glass-ware of the fixtures together, namely the enclosing bowl and shade or reflector of an electric lighting fixture, so that both pieces or glass members of 15 the fixture may be handled as a single unit and whereby said composite unit of glass-ware may be secured to and supported from the canopy or metal shell of the lighting 20 fixture disposed thereabove.

One object of my invention is to provide a construction whereby the glass bowl and the reflector will both be supported in proper relation by comparatively large portions of 25 the fastening means so that the pressure and purchase on said glassware will be distributed to a greater extent and therefore with less likelihood of breakage, than is the case where the usual thumb or set-screw 30 method is employed; my invention at the same time providing greater flexibility in the retaining means than has heretofore been provided, thereby compensating for 35 expansion and contraction in the two members or pieces of glassware to a greater degree than is the case with the fastening means at present employed.

A further object of my invention is to 40 provide fastening means of the character described which may be formed of resilient sheet metal so as to take care of any variations (within certain limits) in size or shape of the respective elements of the fixture; while at the same time providing a construction wherein a single element will lock the respective portions of the glassware holding means in position and eliminate any possible chance of separation or falling 45 of the glassware.

50 Another object of the invention is to provide a holder of the character described whereby the different members or pieces of glassware of the lighting fixtures are so fastened and held together, that a free circulation of air between the juxtaposed por-

tions of the bowl and reflector is made possible, with the result that the various parts of the lighting fixture will be maintained at a lower temperature than is the case in fixtures with fastening means as at present 60 employed; my improved construction being such that the holder or fastening means may be readily secured to the overhead housing or shell of the fixture and at the same time permit of such adjustment that the reflector 65 with the bowl may be adjusted to be disposed in a horizontal plane.

The above enumerated objects and advantages, as well as other advantages inherent in the construction, will be more readily 70 comprehended from the detailed description of the accompanying drawings, wherein:

Figure 1 is a vertical sectional view of a lighting fixture provided with my improved 75 holder or fastening means; the glass bowl being shown in full lines.

Figure 2 is a cross sectional view taken on the line 2—2 of Figure 1 looking in the direction of the arrows.

Figure 3 is a detail perspective view of the main portion of the holder.

Figure 4 is a cross sectional view, taken on the line 4—4 of Figure 1 looking in the direction of the arrows.

In the exemplification of the invention as disclosed in the drawings, the fastening means or holder is illustrated in conjunction with a lighting fixture embodying a top attaching cap or member 15 usually composed 80 of metal; the cap illustrated in the drawings being stamped or spun out of sheet metal and skirted or flared at the bottom to provide an air space intermediate of the other portions of the fixture and the cap. 95 The cap encloses a suitable strap or yoke 16, which may be of spring metal having the upper intermediate portion thereof made sufficiently heavy to be provided with a tapped opening to receive the threaded end 100 of a suspending loop member or other attaching means whereby the fixture may be suspended, yieldingly or otherwise, from the ceiling and at the same time provide for the passage of the electric wires which are 105 secured to the respective contact points or terminals in the socket member 17 which receives the lamp 18. The strap or yoke 16 is formed in any suitable manner so as to have interlocking or holding relation 110

with the reflector and globe holder 19, which is also preferably formed of sheet metal and flared or skirted. The holder 19 is provided with a central opening for the passage of the socket member 17 and lamp therethrough and for the passage of the yoke 16. The lower horizontally disposed portion of the holder 19, preferably at diametrically opposite points, is provided with 10 transversely disposed slots 20, as shown in Figure 1, to receive the threaded posts or stems 21 of the split band or holder 22, see Figures 1 and 3.

The glassware holder 22 is preferably 15 composed of sheet metal so as to be more or less resilient and is formed with a vertical and a horizontal portion or flange and split entirely therethrough as shown at 23 in Figure 3; while at a point diametrically opposite to the split portion 23 the upper or horizontal portion or flange is preferably slit or kerfed as shown at 24 in order to permit expansion or separation of the split or severed portion of the holder beyond normal condition, namely into the maximum expanded 25 condition illustrated in Figure 3. The upper horizontally disposed flange 25 of the holder, at predetermined points, is provided with a plurality of inwardly disposed lips or lugs 30 26, which, in the exemplification, are shown disposed in a triangulated manner so as to provide a plurality of glass-engaging portions at equi-distances apart. The lips 26 are all provided with a downward curvature 35 as clearly shown in Figure 3, and arranged in spaced relation with the vertical portion or flange of the holder 22. The vertical flange portion or side of the holder 22 is provided with a circumferential groove 27 40 on the outside thereof and the lower edge of the vertical flange or portion of the holder, preferably at points coincident with the lips or lugs 26, is provided with an equal number of inwardly and upwardly disposed lugs 45 or lips 28 of such dimensions as to provide a gap or space intermediate of the juxtaposed or correlated lugs or lips 26 and 28, of each pair, in order to provide sufficient 50 space for the neck or rim of the reflector 29. The lugs or lips 28 (which are formed integral with the lower edge of the vertical portion or flange of the band 22) are intended 55 to engage beneath the flanged orifice or flared neck of the reflector 29 while the lugs or lips 26 are adapted to engage with the flanged open end or neck of the globe 30; the holder 22 being maintained in clamping 60 relation with the reflector or shade 29 and the globe 30 by means of a comparatively heavy or stiff bent wire 31, which is in the nature of a split ring and which is adapted to be forced over the top of the holder 22 and be seated in the annular groove 27 formed in the vertical portion or flange of band 22. 65 The split wire ring 31 will maintain the

split band or holder 22 in contracted condition and therefore in clamping or holding relation with the glassware.

My improved holder is especially adapted to firmly hold the two portions of glassware 70 in proper correlation, namely the shade or reflector and the globe or bowl; and the holder is applied by first bringing the two portions of glassware into their proper juxtaposition, that is with the flanged neck or 75 upper end of the globe disposed through the central opening in the shade or reflector and then placing the split holder or member 22 about the flanged opening of the shade or reflector 29 so that the lips or lugs 28 will 80 engage with the flanged neck of the reflector, while the lugs or lips 26 engage with the outer side of the flanged neck of the globe 30; the split holder or member 22 is then compressed so as to bring the separated 85 ends together, or as nearly so as the glassware will permit, and then pressing the resilient wire or split spring member 31 over the top of the holder member 22 until the member 31 enters the circumferential groove 90 27. This will firmly clamp the holder 22 onto the reflector and globe and securely lock the same together so that they in a sense constitute and may be handled as a unit. The united reflector and globe with the 95 member 22 are then held in position, relative to the upper portion of the fixture, namely the shell or holder portion 19, so as to have the posts or stems 21 of the member 22 pass through the slots 20 formed in the shell or 100 holder 19. The apertures 20 in the shell 19, for the passage of the posts or stems 21, are preferably in the nature of slots so as to compensate for any slight variations in the respective members. The holder 22 (with 105 the reflector and globe) is maintained in place by suitable thumb-nuts 32 which screw onto the exposed ends of the stems or posts 21 disposed on the upper outer side of the shell or holder 19, as shown in Figure 1, 110 thereby firmly securing the reflector and globe with my improved holder to the remaining portion of the fixture.

As is apparent from the construction shown and described, both the globe and reflector are each supported and secured in place by means of the comparatively wide lugs or lips 26 and 28, which, like the main or body portion of the holder 22, are composed of thin sheet metal and therefore 115 are resilient and adapted to yield in their pressing relation with the glassware. By reason of the flexibility of the lugs or lips, my improved holder is adapted to not only 120 independently care for the expansion and contraction of the globe and the reflector, but to also take care of a greater amount of expansion and contraction of both pieces of glassware, than is the case with holders as at present employed and provided with 125 130

the well known thumb or set-screw method of securing the glassware in place. It is also apparent that my improved construction is adapted to take care of any variations (within given range) in the size or shape of the flanged or flared necks or openings of the globe or reflector and that the split wire ring will act as a firm lock to maintain the improved holder in position and thus obviate any possibility of the globe or reflector falling or becoming disconnected from the remainder of the fixture. Furthermore, with my improved holder, the two pieces of glassware are secured together in such manner by the lugs or lips that the glassware will be maintained in spaced relation and permit circulation of air between the neck of the bowl or globe and the shade or reflector, with the result that the respective parts of the lighting fixture will be maintained in a cooler condition than would otherwise be the case; at the same time the construction also enables the unit, composed of the globe, reflector and the holder, to be very easily and quickly secured in place by means of two thumb-nuts, provided with suitable knurled surfaces; this method of securing the unit also permitting the proper leveling or adjustment of the glassware in its relation to the main housing or stationarily secured metallic portion of the lighting fixture, namely the upper canopy or shell.

I have shown and described my improved holder for securing a globe and a reflector in place, but it is apparent that it may be employed for securing a single piece of glassware to the housing of the fixture, whether a reflector, or a bowl or globe; and the terms and expressions employed in the specification are merely used as terms of description and not of limitation, as there is no intention in the use of such terms and expressions to exclude any mechanical equivalents for the various features shown and described or to exclude modifications, as certain structural modifications are possible and may be made without, however, departing from the spirit of my invention.

50 What I claim is:—

1. In a lighting fixture, a holder comprising a split annular member of resilient metal provided at top and bottom with inwardly disposed lips or lugs adapted to engage with the flanged neck of separate pieces of glassware of the fixture, a split resilient member adapted to encircle the first mentioned member to maintain the same in contracted condition, and means whereby the first member may be removably secured to the housing or shell of the fixture.

2. In a lighting fixture, a contractible circular member provided with inwardly disposed lips or lugs arranged in pairs, one lug or lip of each pair being disposed inwardly

and downwardly from the inner periphery of the member, while the other lip or lug of each pair is disposed inwardly and upwardly from the outer periphery of the member, and yielding means whereby the member 70 may be yieldingly maintained in contracted condition.

3. In a lighting fixture, a split metal band, angular in cross-section so as to have a vertically disposed portion and a horizontally disposed portion, both portions being provided with inwardly disposed flexible lips or lugs adapted to engage with the glassware of the fixture, and yielding means whereby the split band may be yieldingly 80 maintained in contracted condition.

4. In a lighting fixture, a split sheet metal band, of predetermined circumference, provided with a plurality of inwardly disposed lips or lugs arranged at predetermined 85 points, with one portion of the lips or lugs being disposed inwardly beyond the other portion of the lips or lugs so as to define the circumference of a smaller circle than that defined by the lips or lugs of said other portion, and yielding means whereby the split band may be yieldingly maintained in contracted condition.

5. In a lighting fixture of the character described, a split sheet metal band, angular 95 in cross-section so as to provide a vertically disposed portion and a horizontally disposed portion, the horizontally disposed portion being provided with inwardly and downwardly disposed lips or lugs, while the vertically disposed portion of the band is provided with inwardly and upwardly disposed lips or lugs, with the lips or lugs on the horizontally disposed portion extending into the circumference of a smaller circle than that 100 described by the lips or lugs on the vertically disposed portion, and a resilient member adapted to extend about said band to yieldingly maintain the latter in contracted 105 condition.

6. In a lighting fixture of the character described, a split metal band provided with a plurality of inwardly disposed lips or lugs arranged at predetermined points, in spaced relation, and disposed inwardly so as to define the circumferences of different sized concentric circles, fastening means secured to said band, and a resilient member adapted to extend about said band to yieldingly maintain the latter in contracted condition. 110

7. In a lighting fixture of the character described, a split band provided with a plurality of inwardly disposed lips or lugs arranged in pairs and in spaced relation, with the lips or lugs of each pair being adapted to 115 engage with two different sized pieces of glassware, and a resilient member adapted to encircle said band to yieldingly contract the same, in combination with the shell or holder of the fixture, and adjustable means 120 125 130

whereby the band may be secured to said shell or holder.

8. In a lighting fixture, a contractible member provided at top and bottom with inwardly disposed, resilient lugs or lips of substantial width, a flexible split ring adapted to extend about said member and to normally contract the same, and means secured to said member whereby it may be adjustably secured to the superposed portion of the fixture.

9. In a lighting fixture, a contractible

member consisting of a horizontal portion and a vertical portion, both portions being provided with inwardly disposed resilient lugs or lips of substantial width, means adapted to normally contract said member, and means whereby said member may be secured to the superposed portion of a fixture. 15
